BALLING GUN

Jay D. Weil, Lexington, and William Lee
Nutter, Jr., Georgetown, Ky.

Application August 22, 1951, Serial No. 243,102

11 Claims. (Cl. 128—264)

1

Our invention relates to the provision of an improved novel balling gun.

The use of balling guns to administer capsules to large farm animals is well-known. The instruments of this type which are known to us, however, have certain disadvantages, chief of which is the fact that the cocking of the gun and the insertion of a capsule thereinto must be accomplished in two separate steps, usually necessitating the use of both the operator's hands in manipulating the instrument. Also, the various mechanisms known to us and presently employed with balling guns for effecting discharge of the capsule from the gun are unduly complicated and too often faulty in operation.

Accordingly, it is a primary object of our invention to provide a self-cocking balling gun, by which we mean a balling gun that will automatically cock upon insertion of the capsule into the gun.

It is a further object of our invention to provide improved mechanism for effecting release of the capsule from the gun.

It is also an object of our invention to provide an improved balling gun which is extremely simple to use and which can be manufactured economically.

Yet another object of our invention is to provide a sturdy gun which will stand up under heavy use in connection with the administration of fairly large capsules to livestock. Such a gun will have a minimum of moving parts and those that must move will be subject to a minimum of wear and designed for long use.

Other objects and advantages of our invention will become apparent to one skilled in the art during the course of the following description and from reference to the accompanying drawings in which like numerals are employed to designate like parts throughout, and in which:

Figure 1 is a plan view of the balling gun of our invention.

Figure 2 is a sectional view taken on the line 2—2 of Figure 1.

Figure 3 is an enlarged perspective view of the catch-release mechanism employed in our balling gun.

Figure 4 is a sectional view of the forward end of our balling gun showing the various parts immediately after the capsule has been discharged and before the operator has removed his thumb from the release button.

Figure 5 is a sectional view of the forward end of our gun showing a modification of the capsule-retaining means and the manner in which same is fastened to the gun barrel.

2

In the drawings, we have shown our balling gun as being comprised of a handle 10, a barrel 11, and a capsule housing 12. The barrel 11 is bent downwardly slightly as generally indicated at 13. The purpose of so constructing the barrel will become apparent when the self-cocking mechanism is described.

In the modification of Figures 1 through 4, the capsule-receiving head or housing 12 is screwed onto the end of the barrel as indicated at 14, see especially Figure 2. To this end the extreme end of the barrel 11 is provided with exterior threads which engage with mating threads provided within the end 15 of the housing 12.

15 The capsule-engaging plunger 16 is provided with an enlarged, cup-shaped member 17. The other end of the plunger 16 terminates in an enlarged head 18 which is designed to just nicely slide within the barrel 11. A split ring or the like 19 is placed in the end of the barrel 11 to check forward movement of the plunger 16. In addition, it is preferred that a small rubber or plastic ring or other cushioning member 20 be placed around the plunger 16 and against the

20 head 18 to assist in bringing the plunger to a shockless stop. A rod 22 is seated within a bore provided in the head 18 and pinned thereto as at 21. This rod has a turned down portion 23 which terminates in an enlarged cone-shaped head 24. The detail of this is best seen in Figure 3. The base of the cone-shaped head 24 faces the rod 22. Referring again to Figure 2, it will be noted that a spring 25 surrounds the rod 22 and abuts the head 18 of the plunger 16.

25 A suitable abutment for the other end of this spring is provided within the barrel 11 of the gun. We have shown this abutment as comprising a pair of short pins 26. It is to be understood, however, that other means may be provided, for example, it might be desired simply to crimp the barrel at this point.

Within the barrel 11 there is also provided a tube or elongated member 27 which is pinned to the barrel for pivotal movement as indicated at 28. The forward end of this tube, see especially Figure 3, is provided with a cut-away portion or niche as shown at 29. Also, it is preferred that the forward end of this tube be bent slightly downwardly in the vicinity of this cut-away portion.

45 It will be noted that the forward end of this tube extends past the point 13 at which the barrel itself is bent downwardly.

50 The handle 10 of our balling gun is designed to be screwed onto the rear end of the barrel 11 as indicated at 30. The barrel may be pressed on as an alternative construction. A set screw

31 is also provided to insure exact positioning of the handle 10 with respect to the barrel 11. It will be noted that the handle 10 is hollow. Into the interior of the handle 10 extends the rear portion of the tube or elongated member 27. Fixed in this end of the tube by any suitable means is a plug 32. A release button 33 is provided with a stem 34 which is screwed into the plug 32. The stem is of sufficient length to extend through the plug 32. The handle of the gun is provided with an opening 35 through which the release button 33 projects. Within the handle of the gun 10 a suitable seat 36 is provided for a spring 37 which abuts the plug 32 about the stem 34 of the button 33.

The spring 37 acting against the plug 32 tends to move the tube or elongated member 27 counterclockwise about its pivot 28 so that the forward end of the tube 27 is urged towards the bottom of the downwardly bent portion of the gun barrel. When a capsule 38 is placed within the housing 12, within which it is maintained under slight pressure by reason of the resilient spring 33, and pushed against the member 17 and plunger 18, the head 18 is caused to move against the spring 25 thereby compressing the same. As the head 18 is so moved, the rod 22 and enlarged, cone-shaped head 24 move towards the forward end of the tube 27. As so moved, the point 41 of the head 24 will be substantially, centrally of the gun barrel 11. This point will enter within the end 40 of the tube 27, but because this tube is urged towards the bottom of the gun barrel by the spring 37 just described, the sides of the cone-shaped member 24 will strike the interior wall of the tube 27 at the end 40 with the result that continued movement of the rod 22 will cause the tube 27 to be urged about its pivot 28 in a clockwise direction against the spring 37. When, however, the rod 22 has moved far enough so that the head 24 will clear the front edge 42 of the cut-away portion or niche 29, the spring will urge the tube 27 to snap towards its normal position, with the result that the member 24 will catch within the aperture 29 against the wall 42. At this point, the gun is cocked and the spring 25 is under compression. Also, the capsule 38 is lodged within the housing 12. The spring 39 is so curved as to cut down the interior diameter of the housing (from high point on spring to opposite housing wall) to an extent that such interior diameter is slightly less than the exterior diameter of the capsule. The spring, being flexible, will flatten out when the capsule is forced into the housing. The pressure exerted against the capsule by the so distorted spring serves to hold same in the capsule against the opposite wall.

In order to cause the capsule to be discharged from the gun, it is necessary only for the operator to press the button 33 and move the plug 32 and tube 27 against the action of spring 37. Such depression of the button 33 causes the tube to rotate in clockwise fashion about its pivot 28 with the result that the forward end of the tube will move out of engagement with the cone-shaped head 24. When this happens, the result will be that the spring 25 acting between the pins 26 and head 18 will force the plunger 16 towards the forward end of the barrel 11, the capsule thus being discharged. (The force exerted by compressed spring 25 is greater than that exerted by distorted spring 39.) This action is best seen in Figure 4. With respect to Figure 4, it should be noted that the parts are depicted in their po-

sition as would occur immediately after the button 33 were depressed and before the operator moved his thumb therefrom. This accounts for the upward position of the forward end of the tube 27.

When the operator releases the button 33, the spring 37 will again force this forward end of the tube or elongated member 27 to the lower portion of the barrel 11. The spring 25 forces the head 18 to its lower position wherein it seats through cushion 20 against the retaining ring 19.

In Figure 5, we have shown a modification of our invention. In this modification, it will be noted that we have provided the capsule housing 12 with a projection 43 extending from the rear portion 15 thereof. In this modification, the exterior of the projection 43 is suitably threaded so as to be engageable within the end of the barrel 11. By this construction, the split ring 19 is made unnecessary for the reason that the head 18 will seat through the cushion 20, against the end of the projection 43. In either modification of our invention, it is a feature thereof that the housing 12 may be readily changed to accommodate different sized capsules and the like. Thus, the balling gun of our invention may be used for administering a great many types of medicines to livestock without there being any changes necessary to the actuating mechanism itself; as above indicated, only the capsule housing need be changed.

In operation, a capsule 38 will be pushed into the housing 12 against the member 17 on the plunger 18. Initially the parts will be as shown in Figure 4 with the exception that the forward end 40 of the tube or elongated member 27 will be adjacent the lower part of the barrel 11 for the reason that the operator will not at that time be depressing the button 33. As the capsule is further inserted into the housing 12, the head 18 is forced against the spring 25 until the cone-shaped head 24 engages within the aperture 29 against the wall 42 as above described. Thus, it should be observed that the very act of placing the capsule within the housing 12 serves to cock the gun and ready it for immediate use. When it is desired to discharge the capsule into the animal's mouth or throat, the operator, after placing the gun in proper position with respect to said mouth or throat, merely depresses the button 33 against the spring 37 so as to rock the tube 27 about its pivot 28 and move the forward end thereof out of engagement with the cone-shaped member 24. Upon release of the member 24 from the aperture 29 the spring 25 forces the head and plunger 18 forwardly, thus discharging the capsule from the housing 12.

It is to be understood that although we have shown our invention as embodied in particular structures, we do not intend to be limited by such structures except insofar as they are specifically set forth in the subjoined claims. It is to be further understood that modifications may be made to our invention without departing from the scope and spirit thereof.

Having thus described our invention, what we claim as new and desire to protect by Letters Patent is:

1. A balling gun comprising a barrel, a capsule housing fixed to one end of said barrel, a handle fixed to the other end of said barrel, a plunger slidable within said barrel, a member pivoted in said barrel, means urging said plunger into said housing, means urging said pivoted member to a normal position, means connected to said plun-

er and latching said plunger when moved against said plunger urging means with said pivoted member when said pivoted member is in its normal position, and means in said handle to move said pivoted member from its normal position whereby to release said plunger and connected means from latched engagement with said pivoted member, said plunger on release moving into said housing under the action of said plunger urging means whereby to discharge a capsule from said housing.

2. A balling gun comprising a handle, a barrel fixed to said handle, a capsule housing fixed to said barrel, a plunger extending from said housing into said barrel, an elongated member within said barrel and pivoted thereto, resilient means normally forcing said plunger into said housing, resilient means normally forcing said elongated member about its pivot in a certain direction, means latching said plunger to said elongated member when a capsule is placed in said housing and said plunger thereby forced into said barrel against said first mentioned resilient means, and means in said handle to rock said elongated member about its pivot in the direction opposite said certain direction, whereby said means latching said plunger to said tube is released and said capsule discharged from said gun by the action of said first mentioned resilient means against said plunger.

3. The balling gun of claim 1 including means in said housing of sufficient strength to maintain a said capsule therein against the action of gravity.

4. The balling gun of claim 1 in which said capsule housing is detachably fixed to said barrel whereby different sized housings and capsules may be employed with the same barrel.

5. The balling gun of claim 1 in which said housing has an extension adapted to be screwed into the end of said barrel, said plunger having an enlarged member slidably within said barrel, said plunger sliding within said extension, and cushioning means between said enlarged member and said extension.

6. The balling gun of claim 1 in which said housing is screwed onto the end of said barrel, abutment means located in the end of said barrel, said plunger extending through said abutment means, said plunger having an enlarged member slidably within said barrel, and cushioning means between said enlarged member and said abutment means.

7. The balling gun of claim 1 which the means latching said plunger to said elongated member comprises a rod fixed to said plunger, said rod having an enlarged head, and said elongated member having an aperture of sufficient size to receive said head.

8. The balling gun of claim 7 in which said barrel is bent slightly, said elongated member having an end terminating just past the bend of said barrel, the said end of said elongated member also being bent slightly.

9. The balling gun of claim 7 in which said elongated member comprises a tube and in which said head is cone-shaped, said head being of such size that the point thereof will enter said tube when said tube is in its normal position, continued movement of said rod towards said tube resulting in the sloping sides of said cone-shaped head striking the wall of said tube and raising same about its pivot in a direction opposite said certain direction until said cone-shaped head is moved far enough to be received by said aperture whereupon said head engages the tube portion bounding said aperture, said second mentioned resilient means acting to keep said cone-shaped head and aperture bounding tube portion in engagement.

10. The balling gun of claim 9 in which the means for rocking said tube about its pivot in a direction opposite said certain direction whereby to release said cone-shaped head from said aperture bounding tube portion and thus cause a said capsule to be discharged by action of said first mentioned spring against said plunger comprises a button connected to the end of said tube opposite said aperture, said button extending through an aperture in said handle, said second mentioned resilient means seating in said handle and surrounding a prolongation of said button.

11. The balling gun of claim 10 in which said plunger terminates in an enlarged member slidably within said barrel, said rod being pinned to said enlarged member, and abutment means in said barrel, said first mentioned resilient means comprising a spring surrounding said rod and engaging said enlarged member and said abutment means.
